UNITED STATES PATENT OFFICE

NATHAN SCHWARTZ, OF NEW YORK, N. Y.

BLADE SHARPENER

Application filed November 17, 1930. Serial No. 496,291.

This invention relates generally to the class of sharpening devices for edged tools, and has particular reference to a device which is especially designed for the purpose of sharpening flexible double-edged safety razor blades, the same being in the nature of an improvement upon my copending applications, respectively bearing Serial Nos. 478,729 and 487,312.

10 The present invention broadly aims to provide a device of the indicated character which includes a hollow or concave sharpening surface constructed of a material which offers a greater friction than glass without 15 imparting an abrasive action to the cutting edges of the blade.

The invention further aims to provide a sharpening device of this character which includes a plurality of sharpening surfaces 20 of hollow concave configuration, one of which is of glass and one of which is of a material such as urea formaldehyde, synthetic resin or an equivalent non-abrasive material which offers a greater friction than 25 glass, to provide together with the glass, sharpening surfaces of different characters for imparting a proper cutting edge.

Other objects of the invention reside in the provision of a sharpening device which is 30 simple and compact in its construction, inexpensive to manufacture and which is highly efficient in its purpose.

With the above recited and other objects in view, reference is had to the following description and accompanying drawing, in which there is exhibited one example or embodiment of the invention, while the claims define the actual scope of the same.

In the drawing:

43. Figure 1 is a perspective view illustrating the device in use.

Figure 2 is a transverse sectional view therethrough.

Figure 3 is a longitudinal sectional view 45 thereof.

Referring to the drawing by characters of reference, 5 designates a casing of hard rubber, metal or any other suitable material, having a top wall 6 and side walls 7 and 50 having a slight yieldability. The inner faces

of the side walls 7 are provided with longitudinally extending substantially T-shaped grooves 8 for snugly receiving the T-shaped sides 9 of an arcuate sharpening element 10 which is thus suspended between said side walls. The sharpening element 10 is preferably constructed of glass and presents an inner or upper generally concave or hollow sharpening face 11. The face 11 is further provided with contiguous longitudinally extending convex areas 12, over which the opposite cutting edges A of a flexible double-edged razor blade B are adapted to be moved in frictional contact, to impart a sharpening action thereto, in the manner illustrated in Figures 1 and 2 of the drawing. One end 55 of each groove 8 extends through the front face of the casing 5, while the opposite end 14 of each groove terminates within the rear face of the casing to prevent displacement of the element through the rear end of the casing. The upper wall 6 of the casing is provided with a medially depressed or downwardly bowed arcuate portion 15, within 60 which is frictionally held an arcuate sharpening element 16 having a hollow or concave upper sharpening surface 17. The element 16 is made of a material such as urea formaldehyde, synthetic resin or equivalents thereof, 65 which offers a greater friction or higher coefficient of friction than glass without 70 imparting an abrasive action to the cutting edges of a blade, and is designed to initially receive 75 thereon the blade B for either lateral or longitudinal reciprocations, to impart an initial 80 sharpening action to the blade edges for generating heat for static electricity while leveling or correcting distortion of the blade edges which causes dullness, after which a 85 finished sharpening action is obtained on the surface 12 of the sharpening element 10, where the contiguous convexities of said surface 11 set up a hammering action as the 90 blade is moved laterally thereover, to create a further and final correction of the distortion 95 after the blade has been initially prepared by heating and charging the same with static electricity on the first mentioned surface 17. In practice, the upper wall 6 may 100 be provided with inwardly directed longi-

tudinally extending flanges 18 with which the opposite side edges of the element 16 abut, while a flange 19 may be provided flush with the rear face of the casing to abut with the rear end of the element 16.

While there has been illustrated and described a single and preferred embodiment of the invention, it is to be clearly understood that no limitation is necessarily made to the precise structural details, but that modifications and variations thereof which properly fall within the scope of the claims may be resorted to when found expedient.

What is claimed is:

1. A sharpening element for flexible double-edged razor blades, including a casing, a concave sharpening body, and longitudi-

nally-extending grooves provided in the opposite faces of said casing, said sharpening body having its upper ends appropriately shaped to interfit in the said grooves in the casing for holding the said sharpening body in position in the casing.

2. A sharpening element for flexible double-edged razor blades including a casing having a top wall and depending side walls at opposite side edges of the top wall, a concave sharpening body carried by the top wall and a second concave sharpening body suspended by the side walls, having detachable connection therewith and serving to connect and brace the side walls.
